UNITED STATES PATENT OFFICE.

ERNEST STEAD, OF BINGHAMTON, NEW YORK.

MACHINE FOR PRODUCING CURVED SURFACES.

1,247,735.

Specification of Letters Patent. Patented Nov. 27, 1917.

Application filed June 1, 1915. Serial No. 31,532.

To all whom it may concern:

Be it known that I, ERNEST STEAD, a citizen of the United States of America, and a resident of Binghamton, in the county of 5 Broome, in the State of New York, have invented new and useful Improvements in Machines for Producing Curved Surfaces, of which the following, taken in connection with the accompanying drawings, is a full, 10 clear, and exact description.

This invention relates to certain improvements in machines for producing curved surfaces adapted to be used more particularly in the manufacture of lens grinding 15 and polishing tools, technically known as "laps" and may also be used for cutting the curved surfaces of templets and other implements.

The main object is to provide a simple 20 and compact machine whereby the curved surfaces of tools of this character may be cut or finished with greater precision or accuracy, and at the same time to render the work more expeditious, thereby increasing 25 the output and reducing the cost of production.

Another object is to enable the machine to be easily and quickly adjusted for producing curved surfaces of different radii.

30 A further object is to provide means whereby the same machine may be used for cutting cylindrical, spherical or toric surfaces.

Other objects and uses relating to specific 35 parts of the machine will be brought out in the following description.

In the drawings—

Figures 1 and 2 are, respectively, a top 40 plan and a side elevation of a machine embodying the various features of my invention.

Figs. 3 and 4 are central vertical sectional views taken, respectively, on lines 3—3, and 4—4, Fig. 1.

45 Figs. 5 and 6 are, respectively, a horizontal sectional view taken on line 5—5, Fig. 2, and a vertical sectional view taken on line 6—6, Fig. 1.

Fig. 7 is a side elevation, partly in section, of an attachment for cutting cylindrical surfaces.

Fig. 8 is a vertical sectional view of the same device, except that a portion of the motor is broken away.

Fig. 9 is a horizontal sectional view of 55 the same device, taken on line 9—9, Fig. 7.

Fig. 10 is a face view of an attachment used in connection with the machine for cutting toric surfaces.

Figs. 11 and 12 are, respectively, a vertical sectional view, taken on line 11—11, Fig. 10, and a horizontal sectional view, taken on line 12—12, the same figure.

Fig. 13 is a detail sectional view taken on line 13—13, Fig. 1.

Fig. 14 is a diagrammatic view showing the lines or path of movement of the cutter and its operating means as set for producing a concave curved surface of predetermined radius, the dotted lines below the 70 horizontal line representing another position of those parts for cutting a concave surface of different radius, while the dotted lines above the horizontal line represent one position of the same parts for cutting a convex surface of a given radius.

The particular machine illustrated was designed for use in connection with an ordinary lathe, and for this purpose was provided with a suitable base —1— movable 80 along and upon the ways —2— of an ordinary lathe bed —3—, but in actual practice the entire machine will be constructed as a unit for the particular purpose to which it is adapted with such modifications as may 85 be necessary in carrying out the objects without departing from the spirit thereof.

The head of the lathe is provided with the usual threaded spindle —4— adapted to be driven in any well-known manner and carries a chuck as —5— or equivalent work holder for receiving and retaining a piece of work as —a—, the surface of which is to be cut or finished on curved lines, the work shown in Figs. 2 and 3 being a lap having 90 a spherical convex surface as finished by my improved finishing device, although it will be evident from the foregoing description that similar laps for grinding or polishing cylinder or toric lenses may be finished in 95 the same machine in a manner hereinafter described.

In Fig. 4, however, I have shown a gage plate —6— as carried by the work holder and used in the initial setting up of the machine, but thereafter removed to permit the placing of the work in the work holder.

In forming spherical surfaces upon the work, I make use of the tool holder shown more clearly in Figs. 2 and 4, and comprising a bracket —7— having a relatively movable section —8— for receiving the shank as —9— of a cutting tool —10—, said cutting tool being preferably made separate from the shank and adjustably held in place by a clamp —11— on the adjacent end of said shank whereby the tool may be adjusted endwise or rotarily when necessary.

The section —8— is adjustable horizontally in suitable ways —12— on the lower end of the bracket —7—, and together with the shank —9— of the tool is held in its adjusted position by a clamping screw —13—, as shown more clearly in Figs. 2 and 4.

The tool —10— is adjusted to bring its cutting point or surface in a line extending diametrically through the axis of the work holder and in the initial setting of the machine is placed coincident with said axis, or at the center of the work, after which certain other parts of the machine are adjusted to coöperate with other parts presently described for causing a tool to move diametrically of the work through an arc of predetermined radius to cut the surface of the work to the desired spherical form.

The bracket —7— is secured by bolts —14— to a cross head —15—, which in turn is adjustably mounted upon a horizontally extending supporting arm, —16—, the latter being provided with lengthwise ways —17— along which the bracket is adjustable by means of a screw —18— and nut —19— to properly position the cutting tool —10— with respect to the work, the nut —19— being secured to the cross head —15— by a bolt —20—, while the adjusting screw —18— has its ends reduced and journaled in suitable bearings —21— and —22— on the arm —16—, the outer end of the screw being angular in cross section for engagement by a suitable wrench or hand-crank by which it may be turned.

The inner end of the arm —16— is secured by bolts —23— to a dove-tailed plate —24— which is in sliding engagement with a similarly dove-tailed portion of a main supporting arm —25— (Fig. 4) for moving the tool-holder across the face of the work and also for causing the arm —16— with the tool-holder thereon to swing horizontally with the arm —25—, as previously described.

The arms —16— and —25— are disposed at right angles to each other, the arm —16—

being adjustable along and upon the arm —25— by means of a screw —26— and nut —27—, which latter is secured to the plate —24— by means of a clamping bolt —28—.

The screw —26— and nut —27— are located in a lengthwise groove or recess in the arm —25— to permit the lengthwise sliding movement of the arm —16— and tool holder carried thereby, although the tool holder is located some distance to one side of the sliding interlocking connections between the arms —16— and —25—.

The main supporting arm —25— for the tool holder is journaled in suitable supporting blocks —29— and —29'— to swing horizontally about an axis at right angles to and passing through the axis of the work holder at the cutting point of the tool when the latter is set in its initial or starting position, and for this purpose is provided with a hub —30— journaled in the clamping block —29— and provided with a co-axial shaft or extension —31— screwed therein and journaled in the clamping block —29'— and a superposed standard —32—, which latter is bolted firmly to the block —29'—, as shown more clearly in Figs. 3 and 4.

These clamping blocks —29— and —29'— are connected by bolts —33— which serve to clamp them firmly upon a supporting plate —34— constituting a part of the main supporting frame of the machine and preferably provided with lengthwise and transverse slots —35— and —36— intersecting each other at the axis of movement of the swinging arm —25— to permit said axis to be properly adjusted relatively to the axis of the work holder and the cutting point between the tool and work when the tool is set in its initial position, as previously described, the bolts —33— serving to clamp the blocks —29— and —29'— in their adjusted position firmly upon the plate —34—.

The hub —30— and its extension spindle —31— constitute a relatively long bearing in the blocks —29— and —29'— and standard —32— to steady the action of the swinging arm —25— against undue vibratory movement, and at the same time permit it to be easily rocked in a horizontal plane under the action of its operating mechanism, presently described.

Suitable means is provided for adjusting the supporting blocks —29— and —29'— for the rock arm —25— transversely of the axis of the work holder, said means consisting of a screw —37— having one end journaled in a bearing —38— on the block —29'— and its other end engaged with a stationary nut —39— on the plate —34— and provided with a hand wheel —40— by which the screw may be turned to effect the desired adjustment to bring the axis of the

arm —25— into proper relation with the axis of the work holder.

As previously stated, the arm —16— carrying the supporting bracket —7— for the cutting tool is slidably interlocked with the arm —25— to rock therewith about the axis of the hub —30—, aside from its lengthwise movement thereon, and is provided with a threaded journal bearing or hub —41— upon which is mounted for rotary adjustment one end of a curve regulating arm —42— which is held in place upon the journal bearing —41— by a friction washer —43— and lock nut —44— engaging the threaded end of said bearing.

This arm —42— extends radially from the axis of the bearing —41— and is slidable in a suitable guide-way —45— which is swiveled in a head —46— to turn about an axis 20 parallel with, but some distance to one side of that of the arm —25—, as shown more clearly in Fig. 3, the head —46— being formed of sections secured together by bolts —47— and provided with dove-tailed recesses for receiving a conical pivot —48— on the bearing —45— and also for interlocking engagement with a dove-tailed rib —49— on an adjacent sliding block —50—.

This block —50— is slidably interlocked 30 by means of a dove-tailed joint with a slotted gage bar —51— which is connected by a bracket —52— to the plate —34— and forms a part of the main supporting frame, the plate —34— being supported from the 35 base —1— by means of columns —1'—.

The gage bar —51— is, therefore, fixed and runs parallel with the axis of the work holder and has its front edge provided with a scale suitably calibrated, as shown in Fig. 40 2, along which the gage block —50— is adjustable and is adapted to be clamped in its adjusted position by a set screw —53—. The means for adjusting the gage block —50— consists of a screw —54— and a nut —55—, both of which are movable in the lengthwise slot of the gage bar —51—, the nut —55— being secured to the block —50— by means of a bolt —56—.

The bearings —41— and —45— are provided with pendent gage points —41'— and —45'—, respectively, co-axial with their respective axes to facilitate the setting of the machine after a prescribed formula based upon one-half the chord of an arc of predetermined radius in which the distance between the gage points —41'— and —45'— represents the length of one-half of such chord when the point —41'— is in the turning axis of the arm —25— and the 55 curve regulating arm —42— is at its zero position, as determined by the graduations on the gage bar —51—, it being understood that the block —50— is provided with a

gage mark on its outer face movable along said graduations and registering with the 65 zero point when the parts are set in their initial or starting positions.

It is now clear that if the parts are left in their initially set positions, as shown in the drawings, and the arm —16— is moved 70 lengthwise of the arm —25— by the rotation of the screw —26—, the cutting edge of the tool —10— will be moved in the same straight line radially from the center of the work toward the periphery, while the reverse operation of the screw will cause a reversal of the movement of the tool, but in the same straight line, which would, of course, produce a flat surface upon the work.

It is also evident that if the arm —42— is 80 rocked on its bearing —41— from its initial zero position to or toward the dotted position below the zero line —o—, Fig. 14, and then reclamped in its adjusted position to said bearing, the movement of the arm 85 —16—, carrying said bearing along the arm —25— by the screw —26—, Fig. 3, will cause the arms —16— and —25— together with the tool-holder to swing horizontally about the axis of the bearing —30—, which, 90 in turn, will cause the cutting edge of the tool to travel across the face of the work-holder through an arc of a circle and produce a corresponding concave surface on the work.

On the other hand, if the arm —42— were adjusted to the opposite side of its normal position, it would cause the tool to produce a convex surface on the work, as will be hereinafter more fully described.

The calibration of the scale may be based upon the altitude of an arc of any selected radius and one-half the chord of such an arc as will cause the cutting tool to produce any curvature within the limits 105 commonly employed in making lenses for spectacles and eye-glasses. In this particular instance, the selected radius of the arc is 530 mm. having a chord length of 410 mm. and an altitude of 41.25+ mm., under 110 which conditions the point 45' Fig. 3 would be initially set a distance of 205 mm. or one-half the length of the chord from the point 41', when said point 41' is in the vertical plane of the axis of the work. Then by adjusting the slide —50— a certain distance to one side or the other of its 115 zero position will cause the cutting edge of the tool to move through an arc whose radius is 530 mm. as the tool-carrying arm —16— is moved along the swinging arm —25— or radially of the axis of the spindle —31—.

It is evident, however, that instead of calibrating the scale as shown, it may be 125 graduated in degrees based upon the same

or any other suitable arc, radius, and length, of chord.

In the diagrammatic view shown in Fig. 14, —16— represents the selected radius; —y— the chord of the arc of such radius, and —x— the arc through which the tool is moved when the point —45'— of the bearing —45— carrying one end of the arm, represented by the line —42— is adjusted from its zero position a distance corresponding to the altitude of such arc, and the point —41'— is moved along the arm, represented by the line —25—, thus causing the cutting edge or point of the tool —10— to travel from the point —41'— through the arc represented by the line —x—, it being understood that after the arm —42— has been adjusted in the manner just described about the axis of the hub —41— and at an angle to the arm —16—, said arms are locked in this relation by the lock nut —44—, and that the arms —16— and —25— maintain their right angular relation through the medium of their sliding dove-tailed connections as the arm —16— and adjacent end of the arm —42— attached thereto are moved along the arm —25—, thereby causing said arm —25— to rock about its fixed axis, or the axis of the spindle —31—.

In like manner, the point —45'— may be adjusted to any other angle from its zero position, represented by the line —o— for causing the cutting edge of the tool to produce either concave or convex curvatures of different radii, the concave surfaces being produced by the adjustment of the arm —42— to one side of the zero position, represented by the line —o—, and convex surfaces produced by the adjustment of the same arm to the opposite side of said line.

Feeding means.

The screw —26— which constitutes the direct means for feeding the arm —16— along the arm —25— to cause the cutting tool —10— to travel radially across the face of the work for cutting the desired arc is preferably power-driven and, therefore, automatic, for this purpose is provided with a beveled pinion —57— meshing with a beveled gear —58— on one side of a face gear —59—, said beveled gear and face gear being cast integrally and loosely journaled upon a hub —60— on the clamping block —29—, as shown more clearly in Figs. 3 and 4.

The face gear —59— is driven by a pinion —61— on the lower end of an upright shaft —62— which is journaled in suitable bearings in the clamping blocks —29— and —29'— and is connected by beveled gears —63— and —64— to a countershaft —65—, the latter being journaled in suitable bearings upon the upper portion of the main

supporting frame, as shown more clearly in Figs. 1 and 4.

A similar countershaft —65'— is also journaled upon the upper portion of the frame parallel with the shaft —65—, and preferably at the opposite side of the center 70 of the machine.

In order that each of the shafts —65— and —65'— may be rotated in reverse directions for feeding the tool —10— back and forth across the face of the work, they are provided, respectively, with separate sets of gears —66— and —67— and —66'— and —67'—, loosely mounted thereon and held against endwise movement by pins —68— revolving in annular grooves in said shafts, the adjacent ends of the hubs of said gears being provided with suitable clutch faces adapted to be engaged by the adjacent sides of double-faced clutches —69— and —69'— which are operated by separate shifting levers —70— and —70'—, as shown more clearly in Figs. 1, 2 and 6.

The gears —66— and —66'— are driven in the same direction indicated by arrows —x—, Fig. 1, by means of a pinion —71— and opposite idler gears —72—, the pinion —71— being secured to the shaft of a pulley —73— which is journaled on the main supporting frame and connected by a belt —74— to a pulley —75— on the armature 95 shaft of an electric motor —76—, as shown in Figs. 3 and 6.

The gears —67— and —67'— are driven in a reverse direction from that of the gears —66— and —66'— by means of a pinion 100 —77— on the outer end of the shaft —73'— of the pulley —73—, as shown in Fig. 3, the clutches —69— and —69'— being feathered or splined upon their respective shafts —65— and —65'— to rotate therewith, so 105 that when shifted to a neutral position, or midway between the clutch faces on the adjacent gears, the corresponding shafts will remain at rest, while the gears will continue to rotate in the direction indicated by the 110 arrows.

It is now clear that if the clutch —69— is shifted into engagement with the gear —66— the shaft 65 will be rotated in the direction indicated by arrow —x—, Fig. 1, 115 for feeding the tool —10— in one direction, and when shifted into engagement with the opposite gear —67— the tool will be moved in a reverse direction to cut the desired spherical surface upon the work, as the latter is rotated by the rotation of the mandrel —4— through the medium of any suitable driving mechanism not necessary to herein illustrate or describe.

The operation for cutting spherical surfaces may be briefly described as follows:

Assuming that the adjustable parts of the machine are set in their initial zero posi-

tions for centering the tool —10— and gage pin —41— with the gage plate —6— on the work-holder —5—, as shown in Fig. 4, at which time the axis of the bearing —41— 5 will be coincident with that of the bearing —30—, the tool-supporting bracket —7— is then drawn back by the screw —18— sufficiently to cause the tool —10— to clear the face of the work to be cut, after which the 10 gage plate —6— is removed and replaced by a work-holder with the work therein.

The nut —44— is then loosened and the arm —42— swung laterally by hand to one side or the other of its zero position (according 15 to whether the surface to be cut is concave or convex) until the index mark on the plate —50— registers with the graduation on the scale —51— corresponding to the degree of curvature to be cut, whereupon the 20 nut —41— is retightened to firmly lock the arm —42— to the arm —61—.

The machine is now set in motion which causes the screw —26— to draw the arm —16— and member —42— along the arm 25 —25— which, in turn, moves the cutting tool radially across the face of the work.

This longitudinal movement of the arm —42— through its relatively stationary, but swiveled, bearing —45— causes the arms 30 —16— and —25—, together with the cutting tool —10—, to swing slowly about the axis of the bearing —30— for the arm —25—, while the tool is traveling radially across the face of the rotating work, so that as the tool 35 is fed up to the work at the beginning of each forward or backward movement by the hand operation of the screw —18—, it will cut the work to the desired curvature as indicated on the scale —51—, the adjustment 40 of the screw —18— being repeated as often as necessary to complete the work, or until the cutting edges of the tool reach its initially set position in the produced axis of the bearing —30—.

45 In cutting cylindrical surfaces, it is simply necessary to allow the work to remain at rest by preventing the rotation of the work holder and substituting for the bracket —7— the device shown in Figs. 7, 8 and 9, 50 consisting of the bracket —7— adapted to be secured in place by the same bolts —14— and carrying a rotary mill cutter —10'— of sufficient length to cut the cylindrical surface of the desired width, said cutter being 55 journaled on the bracket —7— and driven from an electric motor —8— through the medium of intermeshing sets of gears —9'— and —11'—, the motor —8— being mounted directly upon the bracket —7—.

60 Otherwise, the cutter is adjusted to the work and operated across the face thereof in substantially the same manner as the cutter —10— and may be used not only for cutting lens grinding and polishing tools, but

also for cutting the patterns or templets 65 used in testing the curvature of such tools and lenses.

On the other hand, if it is desired to cut a toric surface on the work, it is simply necessary to unscrew the chuck —5— from the 70 threaded portion of the mandrel —4— and to substitute therefor the device shown in Figs. 11 and 12, consisting of a face plate —4'— adapted to be screwed upon the threaded portion of the mandrel —4— and 75 provided with a split hub —5'— for receiving and retaining the hub of the work holding chuck —5— and permitting radial adjustment thereof, after which the sides of the split hub may be tightened thereon by 80 means of a clamping screw —5''—, the arm carrying the hub —5'— being adjustable radially of the face plate —4'— by means of a screw —4''—, as shown more clearly in Fig. 11, under which conditions the base —1— 85

and all parts carried thereby would be turned at right angles to the position shown in the drawings, for which purpose, the base is provided with extra V-grooves, Fig. 2, for receiving the ways —2—, thus bringing the 90 arm —25— and screw —26— parallel with the axis of the mandrel —4— in its initial setting, while the axis of the work would be at right angles to that of the mandrel and eccentrically disposed with reference thereto 95 to revolve bodily about the axis of the mandrel;—that is, the work would be adjusted radially of the mandrel to bring its surface to be cut at the desired distance from the axis of revolution to correspond to the radius 100 of one curvature at which such surface is to be cut, and the cutting tool —10— would also be adjusted to the work surface to move in an arc of different radius in the manner 105 previously described for cutting a spherical surface.

In setting the machine for cutting these toric surfaces, the scale may or may not be used, since the skilled operator would be able to determine approximately the angle 110 of setting of the arm —42— to produce a curve of the desired radius and by readjustment could be able to produce the exact curvature required.

In other cases, it may be desired to cut 115 curved surfaces of extremely short radius not within the range of the adjustment of the arm —42—, and it is for this purpose that I have provided the countershaft —65'—, gears —66'— and —67'—, and 120 clutch —69'—.

Rotary motion is transmitted from the shaft —65'— to a parallel shaft —78— by means of intermeshing gears —79— and from said shaft —78— to another shaft 125 —80— by means of beveled gears —81—, the shaft —80— being provided with a worm —82— meshing with a worm gear

—83— which is secured by bolts —84— to the swinging arm —25— coaxial therewith so that when the clutch —69— is thrown into engagement with one of the gears as 5 —66—, slow rocking movement will be transmitted to the arm —25— through the medium of the work and gear —83—, such movement being synchronized with the movement of the part —16— along the arm 10 —25— and is somewhat similar to that produced by the engagement of the arm —42— in the bearing —45— of the structure previously described, although when the worm and gear —82— and —83— are employed, 15 the use of the arm —42— is dispensed with, or at least loosened on the part —41— by the loosening of the nut —44—.

Under these conditions, the use of the scale on the front face of the part —51— 20 would be dispensed with.

What I claim is:

1. In a machine of the character described, the combination of a work holder, a rocking member movable about an axis at 25 right angles to that of the work holder, a tool holder, a support therefor adjustable about said axis to different angles relatively to the rocking member and having an independent movement radially to said axis, 30 means for maintaining the angular relation between said support and rocking member during such radial movement, and means for rocking said member and support as the latter is moved radially to cause the tool to 35 travel in a curvilinear path.

2. In a machine of the character described, the combination of a work holder, a rocking member movable about an axis at right angles to and passing through the 40 axis of the work holder, a tool holder, a support therefor adjustable about an axis parallel with that of the rocking member to different angles relatively to said member and having an independent movement radially 45 to the first named axis, means for maintaining the adjusted angular relation between the rocking member and support during such radial movement of the support, and means for effecting the rocking movement of 50 said member while the support for the tool holder is being moved radially to the first named axis to cause the tool to move in a curvilinear path across the face of the work.

3. In a machine of the character described, the combination with a work holder and a rotary support therefor, of a tool holder, a support for the tool holder movable about an axis in a plane at right angles to that of the support for the work holder 55 and having an independent movement radially to its axis of movement, and means for rocking the support for the tool holder about such axis as it is moved radially there-

to to cause the tool to travel in a curvilinear path across the face of the work.

66

4. In a machine of the character described, a work holder, a tool holder, a support for the tool holder movable about an axis in a plane at right angles to that of the work and having an independent movement radially to such axis, power-driven means for effecting such radial movement, and additional means for rocking the support for the tool holder about its axis as it is moved radially thereto to cause the tool 70 to travel in a curvilinear path across the face of the work.

75

5. In a machine of the character described, the combination of a work holder, a tool holder, a support for the tool holder adjustable about an axis in a plane at right angles to that of the work and having an independent movement radially to such axis, means for feeding the support for the tool holder radially, and additional means for 80 rocking the tool holder support about its axis simultaneously with its radial movement to cause the tool to travel in a curvilinear path across the face of the work.

85

6. In a machine of the character described, the combination of a work holder, a rock arm movable about an axis in a plane at right angles to that of the work, a tool holder, a support therefor slidable along and upon the rock arm toward and from its 95 axis and adjustable to different angles relatively to said arm, means for maintaining the adjusted angular relation between the tool holder support and rock arm, means for feeding the tool holder support lengthwise 100 of said arm, and means for rocking the arm and tool holder support mounted thereon as said support is moved lengthwise of said arm.

90

7. In a machine of the character described, the combination with a work holder, of a rock arm movable about an axis in a plane at right angles to that of the work, a tool holder, a support therefor movable lengthwise of and upon the rock arm toward 110 and from its axis and adjustable to different angles relatively thereto, means for maintaining the adjusted angle between the rock arm and tool holder support during the movement of such support along the rock 115 arm, a guide member turnable about an axis parallel with and at one side of the axis of the rock arm, and a co-operative guide member mounted on the support for the tool holder and movable in the first named 120 guide member as the support for the tool holder is moved along the rock arm to effect the rocking of said arm as the support for the tool holder is moved lengthwise thereof, thereby causing the tool to move in a curvilinear path across the face of the work.

8. In a machine of the character described, the combination of a work-holder, a tool-holder movable about an axis at right angles to that of the work-holder and having 5 an independent movement radial to said axis, means for producing such radial movement, and additional means for gradually turning the first-named means about said axis while the tool-holder is being moved 10 radially thereto.

9. In a machine of the character described, the combination of a rotary work-holder, a swinging member movable about an axis radial to that of the work-holder 15 and provided with a radially extending

guide, a tool-holder, and supporting means therefor including a member movable along said guide and also rotatable therewith about its axis, means for moving said member along the guide, and additional means 20 actuated by said member when moving along the guide for rocking said guide about its axis.

In witness whereof I have hereunto set my hand this 20th day of May, 1915.

ERNEST STEAD.
